BEVERAGE VENDING MACHINE

Gordon H. Little, Baltimore, Md., assignor to Dispensers, Inc., Wilmington, Del., a corporation of Delaware

Application March 23, 1948, Serial No. 16,483

2 Claims. (Cl. 194—13)

1

The present invention relates to beverage vending apparatus, and more particularly to a coin controlled machine for dispensing the ingredients for a carbonated drink into a cup also dispensed by the machine.

One of the objects of the invention is to provide a beverage vending machine in which a cycle of operations for first dispensing a cup to a filling position and then dispensing carbonated water and a flavoring syrup into the cup is performed solely by the insertion of a proper coin in a selected coin chute.

Another object of the invention is to provide a machine of the above character in which a selected one of a plurality of flavoring syrups is automatically dispensed with carbonated water into a pre-dispensed cup solely by the insertion of a proper coin in a selected coin chute.

Another object of the invention is to provide a machine of the above character in which the ingredients are dispensed from refrigerated supplies thereof directly into the cup and in which a small quantity of the water is introduced into the cup prior to the introduction of the syrup.

Still another object of the invention is to provide a machine of the above character in which the flow of ingredients to the cup is by pressure of the carbonating gas, in which the dispensing cycle is electrically controlled, and in which the operating circuit is automatically broken in the event of conditions in the machine precluding the dispensing of a proper drink such as, no cups, inadequate gas pressure, or water, or a full waste receiver.

A further object of the invention is to provide a machine of the above character which includes an electrically operated timing mechanism put in motion by the coin insertion to initiate the flow of the several ingredients and to shut off the flow after a predetermined filling time interval.

A still further object of the invention is to provide a machine of the above character in which a selected one of two flavoring syrups is dispensed into a pre-dispensed cup together with carbonated water in response to the insertion of a coin in a selected coin chute and in which the flow of the selected syrup, once initiated, is continued until the termination of the filling cycle, and, in which flow of the non-selected syrup cannot be initiated, after initiation of flow of the selected syrup, until completion of the filling cycle for the selected syrup.

A still further object of the invention is to provide a machine of the above character which incorporates a secondary timer, initiated by the

2

coin insertion, and operable for an interval slightly in excess of filling time to break the operating circuit in the event the filling cycle runs beyond its predetermined filling time.

5 Another object of the invention is to provide a machine of the above character in which water automatically is supplied to a carbonating unit in relatively small amounts as used, and in which a timing mechanism, pre-set to operate for a time interval slightly in excess to that necessary to supply said amount of water to the carbonator, is set in motion with a water pump and breaks the operating circuit in the event the pump operates beyond the time interval necessary to supply said amount of water to the carbonator.

10 Yet a further object of the invention is to provide a machine of the above character for dispensing carbonated water and one of two flavoring syrups at the selection of the user by insertion of a coin in one of two coin chutes, and in which the operating circuit is normally conditioned to dispense one of the syrups and is switched by a coin inserted for the other syrup to dispense said other syrup.

15 20 25 Another still further object of the invention is to provide a machine of the above character which is fully automatic in operation, is under full electric control responsive to coin insertion, and which is simple and economical in upkeep.

30 35 40 To accomplish the above and other important objects and advantages which will become more apparent during the course of the following description, the invention consists in the parts and combinations hereinafter set forth with the understanding that various changes may be made therein such as in the shape, size and arrangements of the parts, and in the substitution of equivalents, by those skilled in the art, without departing from the spirit of the invention.

45 50 In order to make the invention more clearly understood it has been made the subject of the illustration in the accompanying drawings, wherein a preferred embodiment is shown by way of example.

45 In the drawings:

Figure 1 is a view in perspective of a beverage vending machine according to this invention;

Figure 2 is a view in front elevation of the machine with the casing removed, certain parts being omitted for the sake of clarity;

Figure 3 is a diagrammatic view illustrating the plumbing arrangement between the several components of the machine;

Figure 4 is a schematic wiring diagram of the 55 electric control system of the machine;

Figure 5 is a front elevational view of the filling cycle cam mechanism;

Figure 6 is a view in side elevation of the cam mechanism shown in Figure 5;

Figure 7 is a diagrammatic view of the operating cycle of the cam mechanism shown in Figure 5;

Figure 8 is a front elevational view, partly broken away, of the cup receiving unit of the machine;

Figure 9 is a view in side elevation of the cup receiver; and

Figure 10 is a top plan view, partly broken away of the cup receiver.

Generally, the machine comprises an entirely self contained and enclosed unit which is semi-portable in that it may be readily moved from one location to another and requires only connection to a house current supply and, if desired, a plumbing connection with the house water supply. The machine is operated fully automatically by the user simply and solely by the insertion of a proper coin in a selected one of two coin slots to deliver a drink of the selected flavor. This coin insertion sets up a cycle of operations which first dispenses a paper cup in a rigidly held, but easily removed, upright position in a cup receiver which has an access opening in the front of the machine. Next a flow of carbonated water into the cup is initiated shortly followed by a flow of the syrup for the selected flavor. The water and syrup flow from converging tubes under head pressures of carbon dioxide gas in the respective conduits for the water and syrup to merge and form a partial mixture which is thoroughly completed by turbulence as the liquid enters the cup. At the end of a time interval controlled by a cam timing mechanism, the flow of liquids is shut off and the control circuit returned to its neutral condition preparatory to dispensing a succeeding drink.

The electric operating circuit is conditioned normally for dispensing one of the two flavoring syrups when a coin is inserted in the slot therefor and is switched over to dispense the other flavoring syrup when the coin is inserted in the second slot. When a coin is inserted in one of the slots to initiate the filling cycle for that particular flavor the control for the second flavor is locked out of the circuit until completion of the filling cycle of the first syrup.

Other safety provisions are provided in the control circuit to assure a proper drink and proper operation of the machine by way of a normally closed relay in the main operating circuit which is responsive to inadequate gas pressure, improper water feed, an empty cup receiver, a full waste receiver, and overrun of the filling cycle to open the main control circuit and render the machine inoperative until the defect is remedied.

While in its preferred embodiment, the machine provides for vending plural flavored drinks at the choice of the user, the machine may be readily and easily converted to vend a single flavored drink simply by elimination of one syrup source and one coin chute and its associated selector control circuit.

General description of machine

Referring to Figures 1 and 2 of the drawings, the machine comprises a framework 1 in which are mounted the several components of the machine to be described further. The frame, and the machine components mounted therein, are enclosed in a case 2, the panels of which are pref-

erably arranged to open and expose the interior of the machine for servicing.

The front panel 3 of the case, which may constitute a hinged door adapted to be locked in closed position, is provided with a central opening 4 giving access to a cup receiver indicated generally as 5. The cup receiver receives a cup 6, dispensed from a cup dispenser 7, and the cup may be removed by the user after filling with a selected drink as will be described. At the upper portion of the front panel 3 are a pair of coin slots 8 and 9 suitably designated respectively with the names of the drinks dispensed by the machine. Below the coin slots 8 and 9 is a coin return lever 10 and below this is a coin return cup 11.

Directly behind the coin slots 8 and 9, in closed position of the front panel 3, are respectively, the entrances of a pair of coin chutes 12 and 13 which lead to a common chute 14 and thence to a slug rejector 15. From the slug rejector a pair of chutes 16 and 17 lead respectively to a collection box 182 for accepted coins and to the return coin cup 11 for non-accepted coins or slugs. The slug rejector 15 may be any of a number of well-known types which separate acceptable coins from non-acceptable coins or slugs but, if desired, a coin changer also of any suitable type may be used instead of a slug rejector.

The cup dispenser 7 is mounted in the frame 1 above the cup receiver 5 and may also be of any suitable type but preferably one which will hold a substantial number of paper cups. The cup dispenser illustrated is of a magazine type comprising a circular series of cup holding tubes 18 and is operated by an electric motor 19 to discharge one cup at a time from a magazine tube downwardly through a discharge chute 20, and to index the magazine of cup holding tubes successively to discharge positions when one becomes emptied. The operating mechanism for the cup dispenser forms no part of this invention except for its connection with the operating circuit of the machine, as will be set forth, and will not be described in further detail. It might be pointed out, however, that the magazine of holders is loaded from the top. To facilitate this, the cup dispenser is mounted to the frame for forwardly tilting movement by means of a hinge connection with the frame consisting of a rod 21 which passes through a pair of eyes 22 secured to the bottom of the dispenser and a pair of eyes 23 secured to the frame 1. By means of this construction the whole cup dispenser may be tilted forwardly about the axis of the hinge rod 21 so that the upper end of the magazine of the cup holding tubes will clear the upper portion of the frame 1 and case 2 for loading.

The down chute 20 of the cup dispenser, in normal upright position thereof, registers with an upstanding chute 24 forming a part of the cup dispenser 5. It will be noted, particularly in Figure 9, that the lower edge of the chute 20 and the contiguous edge of the chute 24 are angular so that the cup dispenser may be tilted relatively to the stationary cup receiver chute 24. The cup receiver 5, best illustrated in Figure 8, is constructed of sheet metal to form a rectangular box secured to the frame 1 and having a rear wall 25, side walls 26, a top wall 27, and an open front. Depending from the top wall 27 is a downwardly converging funnel 28 into the upper end of which the cup chute 24 enters. The lower rim 29 of the funnel 28 is circular and of a diameter slightly less than the upper rim of 75 a paper cup to retain a cup therein in an upright

position axially aligned with the funnel and depending therefrom as shown in Figure 8. The forward wall of the funnel 28 and the lower rim 29 are cut away in a circular aperture 30 of somewhat larger diameter than the upper rim of the cup so that the cup may be removed from the receiver by lifting it upwardly and forwardly through the circular cutaway 30.

To provide for illumination of the interior of the cup receiver there is provided an electric lamp 31 mounted on a bracket 32 on one of the side walls 26 and adapted to cast its illumination through a transparent window 33 in the side wall 26.

At the bottom of the cup receiver 5 is an open grid such as a series of spaced parallel rods 34 extending fore and aft of the receiver and held between a pair of channels 35 which extend between the side walls 26 respectively adjacent the forward and rear edges thereof. Below the grid is a trough 36 which slopes downwardly and rearwardly from the forward edge of the cup receiver to carry spillage into a waste receiver 37 removably supported by the frame 1 below the cup receiver. This waste receiver comprises an open top tank and is provided with a float 38 carried by an arm 39 adapted, when the level of waste in the receiver reaches a predetermined height, to close a circuit breaking switch 40, as will be further set forth.

Mounted in the frame 1 to the rear of the cup receiver and the waste receiver is a water tank 41 and at the left hand side of the frame, as seen in Figure 2, is mounted a cooler-carbonator unit 42. Above and below the unit 42 are respectively mounted a syrup tank 43 and a second syrup tank 44, each adapted to contain a different flavoring syrup ingredient for a drink. Below the syrup tank 44 is a water pump and motor unit 45 and behind the tanks 43 and 44 and cooler-carbonator unit 42 is a bracket 46 adapted to receive and hold a commercial tank 47 of compressed carbon dioxide gas. On the floor of the frame 1 is mounted a mechanical refrigeration unit 48 consisting, as seen in Figure 3, of the usual compressor 49, motor 50, liquid receiver 51, heat exchanger 52, gas drier 53 and expansion valve 54.

The water tank 41, the syrup tanks 43 and 44 and the waste receiver 37 may be removably mounted in the frame 1 to facilitate cleaning and sterilizing. The water and syrup tanks are provided with closed filling openings, those for the syrup tanks being pressure tight, to permit filling tanks with the drink ingredients.

No plumbing or wiring is shown in the general assembly view, Figure 1, but are shown diagrammatically respectively in Figures 3 and 4.

Plumbing arrangement

As seen in Figure 3, the water tank 41 is connected through a valve 55 and a T 56 with an inlet pipe 57 and a discharge pipe 58. The inlet pipe 57 is provided with a valve 59 and a water connection 60 to connect with a house water supply. The discharge pipe 58 has positioned therein an air expansion chamber 61 and connections through a filter 62 and a solenoid valve 63 with an input side of the water pump 45. It will be readily apparent from the above that water may be supplied to the machine by direct connection with the house supply through the connection 60. However, the tank 41, which may be filled independently of the connection 60, provides that the machine may be installed in loca-

tions where a water connection is not conveniently available, or temporarily installed without plumbing connections such as for spotting the machine for best location.

The discharge side of the pump 45 connects through a pipe 64 and a water-gas mixing valve 65 with a relatively small tank 66 forming the carbonator component of the cooler-carbonator unit 42. This unit is of a commercial type and does not form a part of the invention, apart from the general combination therewith. Briefly, however, it comprises a shell 67 having a connection through a conventional refrigerating circuit with the refrigerator unit 48. The shell 67 contains the carbonator tank 66 and also a pair of cooling coils 68 and 69 which communicate respectively through pipes 70 and 71 respectively with the bottoms of the syrup tanks 43 and 44.

Carbonating gas is supplied to the carbonator mixing valve 65 from the CO₂ tank 47 through a pipe line 72 and a pressure regulator 73 to a T 74 and thence through a pipe 75 to the mixing valve 65. The T 74 also connects through a second pressure regulating valve 76 and a pipe line 77 with the head spaces respectively of the syrup tanks 43 and 44 to establish a head pressure and flow from these tanks. If desired, pressure relief may be provided from the gas supply such as through a pressure relief valve 78. It will be seen from the above that the carbonating gas pressure and the syrup tank head pressure may be independently controlled and regulated as desired.

The opposite ends of the cooling coils 68 and 69 connect respectively with pipe lines 79 and 80 while the carbonator tank 66 is provided with a discharge pipe 81. The pipes 79, 80 and 81 are each provided with a solenoid valve designated respectively as 82, 83 and 84 and the syrup pipes 79 and 80 have their outlet ends converging angularly toward the outlet end of the water pipe 81 to constitute in effect a mixing nozzle which is positioned within the cup receiver 5 above the position of a cup therein as indicated in Figures 8 and 10. As will be explained further, the valves 82, 83 and 84 are individually controlled, the valve 82 or 83 being opened, at the choice of a user, with the water valve 84 to supply one of the two syrups as a flavoring ingredient with carbonating water to make a drink. It is to be understood that the pipes 79 or 80 and 81 discharge directly into the cup and it will be further understood that because of the angular relationship between the tanks 43 and 44 and the discharge ends of the syrup pipes with the water pipe that there will be a confluence and mixing of syrup and water as they flow into the cup. A further co-mingling and intimate mixture will be made in the cup itself because of turbulence created therein by the discharging liquids. The above arrangement has been found very advantageous over pre-mixing the ingredients before they flow to the cup, such as by the use of mixing valves or chambers, in that contamination of a succeeding drink by a prior, different flavoring syrup is eliminated.

Constituting an important part of the invention is the coin actuated electric control system as shown schematically in Figure 4 and the filling cycle timer indicated generally as 85 and shown in Figures 5, 6 and 7.

Filling timer

Referring to Figures 5 and 6 the filling timer 85 comprises a frame 86 in which is rotatably

journalled a cam shaft 87. The timer may be conveniently located within the operating mechanism, housing 88 of the cup dispenser 7 and the cam shaft driven by the dispenser motor 19 such as through a gear connection indicated generally as 89. The motor 19 is a constant speed type operating at twelve R. P. M. and moves the cam shaft 87 one revolution in five seconds. It might be stated here that the pipe sizes, gas pressures, etc. are calculated so as to fill a cup with a drink within slightly less than one cycle of the cam shaft 87 or slightly over four seconds. Should the timer 85 exceed its cycle in five seconds there is provided a circuit breaking timer 90 (see Figure 4) which comprises a small electric synchronous motor 91 which moves an arm 92 adapted to engage and close a normally open switch 93 at the end of a pre-set cycle of operation of the motor 91. This cycle of operation of the motor 91 may be set to a period slightly in excess of the five second cycle of operation of the timer 85, for example, eight seconds, and at the end of this period will engage the switch 93 to open a circuit breaker 94 in the main operating circuit for the machine as will be further described.

The cam shaft 87 is milled to form four axially displaced cams designated respectively 95, 96, 97 and 98 as seen from left to right in Figures 4 and 5. These cams cooperate respectively with followers 99, 100, 101 and 102, each carried on the free end of a pivoted arm 103 to actuate respectively a series of switches 104, 105, 106 and 107 carried by the frame 86. The switch 104, as seen in Figure 4, is a double throw switch having a normally closed and normally open contact. The switch 105 is a single throw normally open switch, the switch 106 is a single throw normally open switch and the switch 107 is a single throw normally closed switch. The normal positions of the above named switches and other switches and relay contacts and the normal position of the cam shaft 87 are the positions occupied between operations of the machine.

The arrangement of the cams 95, 96, 97 and 98 is best seen in the diagram Figure 7, where the cam shaft 87 is shown divided into five one second intervals of its revolution. Each cam is a milled segment of the periphery of the cam shaft forming low and high portions of the periphery of this shaft. As seen in Figure 7 the high portion of the cam 95, or "five second cam," which controls the period of operation of the timer, extends from about one-half second from the zero or normal position of the cam shaft around counter to the direction of rotation to about one-half second before the five second position or slightly over four seconds. The high portion of the cam 96 or "water cam," which controls the duration of water discharge, extends from the one second position around to about the termination of the high portion of the cam 95. The high portion of the cam 97 or "syrup discharge cam," which controls the duration of syrup discharge, extends from a fraction of a second beyond the starting of the high portion of the water cam 96 around to a small fraction of a second before the end of the four second position. The high portion of the cam 98 or "syrup selector cam," which controls the operation of holding circuits to be described, starts just a small fraction of a second prior to the termination of the cam cycle or zero position and extends around the cam shaft to just a frac-

tion of a second after to the four second interval of revolution of the cam shaft.

Electrical control circuit

5 Referring now to Figure 4 it will be seen that coin chute 13 is designated "No. 1 Syrup" while chute 12 is designated "No. 2 Syrup." Coin chute 16 has associated therewith a normally open switch 108, which will be momentarily closed by an accepted coin passing through either chute 12 or 13 and through the chute 16 to the coin box 182. The coin chute 12 for selection of the flavor designated "No. 2 Syrup," has associated therewith a normally open switch 109 which will be momentarily closed by a coin inserted in the chute 12. The chute 13, for selection of "No. 1 Syrup," is open, i. e. has no switch, while the non-accepted coin or slug chute 17 has a normally closed switch 110 associated therewith and which will be momentarily opened by a non-accepted coin or slug passing through the chute 17.

20 Electric operating power is supplied from a 110 v. A. C. house line through a "hot" power line 111 and a "return" line 112 in which are connected, in series, a pair of power switches 113 and 114. The switch 113 is preferably located outside the casing 2 while the switch 114 is located inside the casing. The switch 113 may include, or be, a motor overload circuit breaker to protect the motors. The hot line 111 contains the contacts of a normally closed relay 94, beyond the switch 114, and which is opened upon energization of its winding 115 as will be described.

25 Tracing the control circuit further, the hot line 111 connects with one contact of the switch 108, the other contact of which connects through a lead 116 with one end of the winding 117 of a starting relay 118, the opposite end of the winding 117 connecting with the return line 112 through a lead 119. The relay 118 has three sets of normally open contacts 120, 121 and 122 which are closed by energization of the winding 117. The contacts 120 are in a lead 123 which connects with one side of the cup dispenser-filling timer motor 91, the opposite side of which is connected with the return line 112. The lead 123 and return line 112 also connect with an operations counter 124. The lead 123 also connects with one side of the eight second timer motor 91 through a lead 125 and normally closed, series connected, contacts of three double throw switches, the first of which is the "full waste" switch 40, the second, a switch 126 responsive to a predetermined minimum gas pressure and the third, a switch 127 responsive to an empty cup dispenser. The other side of the timer motor 91 connects with the return line 112 through a lead 128. The timer motor lead 125 also connects through the lead 123 and a lead 129 with the open contact of the cam switch 104 and thence through its contactor and a lead 130 with the hot line 111.

30 Thus closing the switch 108 and energizing the relay 118 starts the motors 19 and 91 to dispense a cup, start rotation of the cam shaft 87 and start the timer 90. Since the switch 108 is closed momentarily, a holding circuit for the relay 118 is provided from the winding lead 116 through relay contacts 121, a lead 131 and the normally closed switch 107 to the hot power line 111. The 35 third set of relay contacts 122 are connected in parallel with the contacts of the coin return switch 110 through a pair of leads 132 and 133, the lead 132 also connecting through lead 131 and switch 107 with the hot line 111.

9445 9450

motor 19 is also provided from hot line 111, through lead 130, normally open contacts of switch 104, lead 129 and motor lead 123.

The hot line 111 connects through lead 130, normally closed contacts of switch 104, a lead 134, switch 109 and a lead 135 with one end of the winding 140 of a selector relay 141, the opposite end of the winding 140 connecting with the return power line 112. The relay 141 has three sets of contacts, the upper set 143 being holding contacts, normally open and when closed connecting the lead 135 through a lead 144 with lead 133 and thence through switches 110 and 107 to hot line 111. The second set of contacts 145 are normally open and connect the hot line 111 through a lead 146, syrup discharge cam switch 106, and a lead 147 with one end of the solenoid winding 148 of the No. 2 Syrup valve 83, the opposite end of which is connected to return line 112. The third set of contacts 149 of relay 141 are normally closed and connect the lead 147 with a lead 150 to one end of the solenoid winding 151 of the No. 1 Syrup valve 82, the opposite end of which is likewise connected to return power line 112. Thus, when the switch 109 is momentarily closed by a coin passing through the chute 12, the relay 141 is energized and held through its holding circuit, the contacts 149, controlling the No. 1 Syrup valve 83, are opened and the contacts 145, controlling the No. 2 Syrup valve, are closed.

The water discharge solenoid valve 84 is connected with the power source by a lead 152 from the hot line 111, through the water cam switch 105 to the water valve solenoid winding 153 and thence to the return line 112.

As described above, water is supplied to the carbonator 66, either directly from a connection with a water main or from the supply tank 41 and through the solenoid inlet valve 63 by means of the motor operated pump 45. The water pump motor 45 and inlet solenoid valve are operated simultaneously and are controlled independently of the coin controlled dispensing circuit in response to high-low water levels in the carbonator. While any suitable means which will provide such control is satisfactory, the following has been found efficient.

The hot line 111 is connected through a lead 154 with one side of the motor 45 and solenoid valve 63, through a pair of contacts 156 and 157 of a water feed control relay 158. The opposite side of the motor 45 and valve 63 connect with the return lines through a lead 155 to the return power line 112. Another pair of contacts 159 and 160 of the relay 158 connect respectively through leads 161 and 162 with a pair of electrodes 163 and 164 of different lengths with their lower ends positioned at different levels in the carbonator tank 66. The contacts 156, 157 and 159, 160 are respectively adapted to be bridged by contactors 165 and 166 carried by an armature 167. The armature 167 is attracted by an A shaped core 168 having a primary winding 169 connected across the line 111-112, and secondary winding 170 connected between the shorter electrode 163 and the metallic tank 66 as indicated by the ground symbols 171.

The contactor bridges 165 and 166 are arranged so that the contacts 156 and 157 are closed and the contacts 159 and 160 are opened when the armature 167 is not attracted by the core 168 and the reverse obtained when the armature is attracted by the core 168. The first condition obtains, and the motor 45 and solenoid valve 63 are energized, when the water in

the carbonator is at its low limit level. When water in the carbonator is at low level, the primary 169 sets up a magnetic flux in the A shaped core which follows a path of least resistance through the lower bar carrying the secondary winding 170 and the armature 167 is not attracted to the core. The magnetic flux induces voltage in the secondary winding 170 but no current flows if the secondary circuit is open through the electrodes 163 and 164. In this position of the relay 158 water will be pumped into the carbonator until it contacts the shorter electrode, thereby connecting the shorter electrode with the longer, and closing the secondary circuit and causing current to flow through the secondary winding. When this happens a bucking action is set up in the bar within the secondary winding diverting the lines of magnetic force to the legs of the core which pulls the armature upwardly opening the contacts 156, and 157 to break the circuit to the motor 45 and valve 63, and closing the contacts 159 and 160. The closed contacts 159 and 160 close a holding circuit through the secondary 170 from ground through the water in the carbonator and the longer electrode 164. This holding circuit is maintained until the water level drops to the point where it breaks contact with the longer electrode when the secondary circuit will be broken, the relay will drop out and the contacts 156, 157 will again close to reenergize the motor 45 and valve 63.

Associated with the water feed control is a circuit breaking timer 172, similar to the timer 90 and which comprises a small synchronous motor 173 moving an arm 174 to engage and close a normally open switch 175 after a preset time interval. The arm 174 may be set to close the switch 175 after a time slightly in excess of that required for the pump 45 to fill the carbonator to desired level, for example, 60 seconds. The timer motor 173 is connected with the hot line 111 through lead 154 and contacts 156 and 157 by a lead 176, and by a lead 177 to the line 155 and thence to the return power line 112. Thus, the timer motor operates simultaneously with the motor 45. In the event, however, the relay 158 fails to function to shut off the water motor 45, the timer motor 173 will continue to run until it closes the switch 175. As seen in Figure 4, the switches 175 and 93 are connected in parallel and connect the hot line 111 with one end of the magnet winding 115 of the normally closed relay 94, the opposite end of which is connected with the return line 112. Thus, it will be seen that when either of the switches 175 or 93 close, circuit is completed to energize the relay 94 and open the main power circuit. Preferably, the timers 90 and 172 are of the type that automatically return to their starting positions if their set running time is not completed, but if completed to close their circuit breaker energizing switches, must be reset manually. Such timers are commercial products and further description is not thought necessary.

To return to the switches 40, 126 and 127, it will be recalled that the normally closed, series connected contacts of these switches connect the timer motor 91 in the power circuit through the lead 125 and contacts 120 of the starting relay 118 and through lines 125 and 129 and the normally open contacts of the five second cam switch 104 which contacts, when closed by the cam 95, form a holding circuit for the motor 91 independently of the relay 118. Thus, should the cam mechanism fail to break the holding

circuits for the relay 118 or for the motor 19, the timer 90 would continue to run its set interval and open the relay 94 to open the main power circuit.

The normally open contact of the switches 40, 126 and 127 are connected in series and to the hot line 111, through a lead 178. These switches, as stated, are mechanically responsive to conditions respectively of a full waste receiver, no gas pressure, and an empty cup dispenser so that when any one of these conditions prevail, the corresponding switch will be actuated to close its normally open contact and connect the timer motor 91 directly in the power line. This sets the motor 91 in operation and at the end of its operating time interval, closes the switch 93 to energize the relay 94 and opens the main control circuit to render the machine inoperative.

The cup receiver lamp 31 and additional lamps, such as lamps 179 and 180 lighting respectively the legends for the coin slots 8 and 9 are connected directly across the main line 111 and 112. The refrigerator motor 50 is likewise connected directly across the main power line through a thermostatic control 181 so that the lights and refrigeration unit are operated independently of the control circuit.

Operation

The operation of the machine will best be understood by reference to Figures 3 and 4. Suppose first, by way of example, a customer desires a drink mixed with the No. 1 flavoring syrup. He inserts a coin in the slot 9, labeled for this flavor and the coin drops through the chute 13 into the chute 14 and thence into the slug rejector 15. If the coin is of improper value or otherwise not acceptable, the slug rejector automatically, in usual manner, diverts the coin to the chute 17 from which it moves into the coin return cup 11 upon actuation of the return lever 10. If the coin is acceptable, however, it moves through the chute 16 and in to the collection box 182. In its passage through the chute 16 it momentarily closes the switch 108.

Closing of the switch 108 completes a circuit from the hot line 111 through the lead 116 and winding 117 of the relay 118 and through the lead 119 to the return power line 112. Thus energized, the relay 118 drops in, closing the contacts 120, 121 and 122. The contacts 120 close the circuit to the motor 19 and counter 124, registering an operation, dispensing a cup to the receiver 5 and starting the cam timer 85 in its cycle. The holding circuit for the relay 118 is closed through the contacts 121 from hot line 111, closed switch 107, leads 131 and 132, contacts 121, lead 116, winding 117 and lead 119 to return line 112, which maintains the relay 118 closed until the switch 107 opens as later described. Closing of contacts 120 also completes a circuit to the timer 90 which is from the hot line 111, lead 123, contacts 120, lead 125, closed contacts of switches 40, 126 and 127 to motor 91 and thence through lead 128 to the return line 112 to start movement of the arm 92 toward the circuit breaking switch 93.

When the cam shaft 87 has rotated about the first one-half second of its cycle the normally closed contact of switch 104 is opened and the normally opened contact is closed establishing a second holding circuit for the motor 19 from line 111 through leads 130, 129 and 123 to the motor and thence to return lead 112. A holding circuit is thus also established for the timer motor

through the lead 129 to the leads 123 and 125. This position of the cam shaft 87 is indicated in Figure 7 as "five seconds on." It will be appreciated that the cam shaft 87 is viewed from opposite ends in Figures 4 and 7, and, hence, appears to rotate in a clockwise direction in Figure 7 and a counter-clockwise direction in Figure 4. When the cam shaft 87 reaches the "one second" position of its cycle the switch 105 is closed completing a circuit from hot line 111 through lead 152, switch 105, lead 153 to the solenoid winding 153' of the water valve 84 and thence to return line 112 to open the water valve 84. Water and carbon dioxide gas have been supplied to the refrigerated carbonator 66 as described above and now flows under carbonator pressure through the water pipe 81 and valve 84 into the cup in the cup in the receiver 5. About an eighth of a second later in the cycle of the cam shaft 87, the switch 106 is closed, establishing an energizing circuit for the No. 1 Syrup valve 82 from the line 111 through lead 146, switch 106, lead 147, closed contacts 149 of selector relay 141, lead 150 and solenoid winding 151 of the valve 82 to return line 112 to open the No. 1 Syrup valve. It will be recalled that the head spaces of the syrup tanks 43 and 44 are pressurized by the CO₂ gas and syrup now flows from the tank 43 through the pipe 70, cooling coil 68, pipe 79 and valve 82 into the cup. The discharge end of the pipe 79 being inclined toward the water pipe 81 causes a confluence and mixing of the syrup and water as they flow into the cup.

The cam shaft 87 continues to rotate until it reaches approximately the four second period of its cycle when the switch 106 will open breaking the circuit to the No. 1 Syrup solenoid valve and shutting off the flow of syrup. About three-fourths of a second later the cam 96 will have reached a position to allow the switch 105 to open and break the circuit to the water solenoid valve 84 to shut off the flow of water. It will be understood that the times in the cam cycle mentioned above are arbitrary and are calculated for filling a particular cup to a desired level.

About one-half second before the switch 105 opens, the cam 98 will have rotated to a point where the follower 102 starts descending to the low portion of the cam surface 98 to open the holding switch 107 and break the holding circuit to the relay 118 allowing this relay to drop out and return to its normal position ready for a succeeding operation. The lowest portion of the cam surface 98 is reached at about the time the switch 105 opens. The low of the cam 98 is very short and the switch 107 opens only momentarily returning almost immediately to its normal closed condition. About a half second after the switch 107 is actuated the cam shaft 87 completes its revolution and the follower 99 drops into the low of the cam 95 returning the switch 104 to its normal position and breaking the holding circuit to the motor 19 to stop the cam shaft in its normal position ready for another cycle of operation.

It will be noted that the normally closed contacts of the switch 104 and the contacts of the switch 109 are in series in the energizing circuit 70 for the selector relay winding 141. Therefore, when a cycle of operation is started as above described and the normally closed contacts of the switch 104 are opened, the relay 141 is rendered inoperative with the contacts 145 in the No. 2 Syrup valve circuit open. Thus, the No. 2 Syrup

13

valve cannot be energized by a coin inserted in the chute 12 until the circuit returns to its normal condition at the end of the filling cycle. It will be understood that the slug rejector 15 may be wired between the lead 129 and line 112 as indicated by dotted leads 200 and 201 to reject all coins inserted during an operating cycle to prevent "jack-potting."

To obtain a drink flavored with the No. 2 Syrup the customer inserts his coin into the chute 12 where it momentarily closes the switch 109 and energizes the selector relay winding 140 by closing a circuit from power line 111 through lead 130, closed contacts of switch 104, lead 134, switch 109, lead 135 and winding 140 to return lead 112. Energizing relay 141 opens contacts 149, in the energizing circuit for the No. 1 Syrup valve, and closes contacts 145 in the energizing circuit for the No. 2 Syrup valve 83, conditioning this valve for opening.

The relay 141 will be maintained energized through its holding circuit from hot line 111 through closed switch 107, leads 131 and 132, closed switch 110, leads 133, 144 and 135, relay contacts 143, and winding 140 to return lead 112.

Now if the inserted coin is acceptable, it passes through the slug rejector and chute 16 where it actuates the switch 108 and initiates the cycle of operations described above except in this case the solenoid 148 for the valve 83 is energized and permits flow of the No. 2 Syrup. The filling cycle continues as above until the holding circuit for the relays 118 and 141 are broken by the cam 98 just prior to the end of the timer cycle.

In the event the inserted coin is not acceptable it passes through the chute 17 and opens momentarily the switch 110. It will be recalled that this switch is in the holding circuit for the selector relay 141 and if opened breaks the holding circuit allowing the selector relay to drop out and return to its normal condition.

In the event of a temporary power failure before the completion of a filling cycle all motors will, of course, stop, all valves close, and the relays 118 and 141 will drop out. The normally open contact of the switch 104 will be closed, however, maintaining the holding circuits described above for the motors 19 and 91 and upon resumption of power these motors will resume operation to complete their cycles and return the circuit to its normal condition. The water discharge valve 84 and the syrup valve 82 will remain open and the cup, if left in position, will be filled.

From the foregoing it will be seen that the machine of this invention is fully automatic in operation and controls the dispensing of a cup and the selection and dispensing of differently flavored drinks simply and solely by the insertion of an acceptable coin in the proper coin slot for the selected drink, the machine completing its filling cycle in each operation and automatically returning to its normal condition for subsequent use after each operation. The dispensing control system is fully electric and apart from the operating motors, cup dispenser release and indexing mechanism and dispensing cycle timing cam there are substantially no moving parts subject to wear or requiring lubrication and all parts of the machine are readily accessible for servicing.

I claim:

1. In the beverage vending machine of the type for dispensing ingredients for differently flavored beverages at a common station in response to the insertion of a coin, said machine including indi-

14

vidual solenoid valves for controlling the dispensing of ingredients respectively from supplies of two flavoring syrups and carbonated water, energizing circuits for the valves, the circuit for one syrup valve having normally closed contacts therein and the circuit for the other syrup valve having normally open contacts therein, a pair of flavor selecting coin chutes, a common chute communicating therewith, means including a switch associated with said common chute and actuated by a coin passing therethrough to initiate a cycle of operations first to connect and subsequently disconnect said circuits with a powerline, and means including a switch in one of said selector chutes and actuated by a coin passing therethrough to open said normally closed contacts and close said normally open contacts.

2. In a beverage vending machine of the type for selectively dispensing one of two flavoring syrups together with carbonated water into a cup in response to the insertion of a coin, means including individual solenoid valves for controlling the dispensing of said syrups respectively from supplies thereof, energizing circuits for the valves, a pair of flavor selecting coin chutes and a common chute communicating therewith, relay means having normally closed contacts in the circuit for one valve and normally open contacts in the circuit for the other valve, an energizing circuit for the relay including a normally open switch associated with one selecting chute and momentarily closed by a coin passing therethrough to close said open contacts and open said closed contacts, motor operated timing mechanism including switch means in the valve energizing circuits actuated within a predetermined cycle of said mechanism to complete and break said valve circuits, a motor energizing circuit including a switch in said common chute and actuated by a coin passing therethrough from the selector chutes to initiate said cycle, a relay holding circuit including a normally closed switch momentarily opened by said mechanism subsequent to breaking of the valve circuits to return the contacts to normal condition, a holding circuit for the motor including a normally open switch actuated by said mechanism to close upon initiation of said cycle and open upon termination of said cycle.
